United States Patent Office.

JOHN CASH AND JOSEPH CASH, OF COVENTRY, ENGLAND.

Design No. 4,577, dated January 17, 1871.

DESIGN FOR DRESS-TRIMMING.

The Schedule referred to in these Letters Patent and making part of the same.

Whom it may concern:

it is known that we, JOHN CASH and JOSEPH CASH, of Coventry, in the county of Warwick, England, have invented a new and original Design for Dress-Trimming, the nature and extent of which will be understood by reference to the accompanying photograph forming part of this specification. The nature of our design is fully represented in the enclosed photograph, to which reference is made.

We claim as our invention—

The design for dress-trimming, as shown.

JOHN CASH.
JOSEPH CASH.
